UNITED STATES PATENT OFFICE.

HENRY W. O'NEILL, OF BROOKLYN, NEW YORK, ASSIGNOR TO GRAY NATIONAL TELAUTOGRAPH COMPANY, OF NEW YORK, N. Y., A CORPORATION OF VIRGINIA.

TELAUTOGRAPHIC APPARATUS.

1,128,493.

Specification of Letters Patent. Patented Feb. 16, 1915.

Application filed March 7, 1912. Serial No. 682,116.

To all whom it may concern:

Be it known that I, HENRY W. O'NEILL, a citizen of the United States, residing at Brooklyn, county of Kings, and State of New York, have invented certain new and useful Improvements in Telautographic Apparatus, fully described and represented in the following specification and the accompanying drawings, forming a part of the same.

This invention relates to improvements in telautographs of the variable current-strength type, such as shown and described, for example, in Letters Patent of the United States No. 954,150, granted to George S. Tiffany April 5, 1910.

The improvements of the present invention have reference particularly to means for vibrating the pen moving parts in the receiving instrument so as to reduce frictional resistance to the movement of such parts while the instrument is receiving.

The improvements of the present invention have reference also to means for controlling, from the transmitting station, the movements of the receiving pen in the distant receiving instrument to and from the writing platen or record strip of that instrument as the transmitting tracer is moved to and from its writing platen or record strip.

In the accompanying drawings—Figure 1 is a diagrammatic view of a telautograph station, shown, for convenience, in transmitting condition; and Fig. 2 is a like view of another station, shown, for convenience, as receiving from the station illustrated in Fig. 1.

For convenience, I have, in these drawings, illustrated the improvements constituting my invention in connection with a telautographic system generally the same as that shown and described in detail in an application of George S. Tiffany, filed February 24, 1912, Serial Number 679,598, but it will be understood, of course, that the present improvements are not to be limited to the particular system there shown and described. It will also be understood that in the accompanying drawings I have illus-

trated only so much of said system as is necessary to a proper understanding of the present improvements.

Each station comprises a transmitter and a receiver, and in the number, relative arrangement, and construction and operation of parts, one station is the counterpart of the other. Therefore, in the following description, references will be made to either station, according as convenience in tracing circuits may dictate, corresponding reference numerals being used in both figures of the drawings, followed, however, in Fig. 2, by the reference letter "a."

Each transmitter comprises a pair of rheostats 1, 2, included in a normally opened local circuit from a source of electric energy, for example, a motor generator 3, the negative pole of which is grounded at 4, this local current supplying circuit being controlled by an electric master switch mechanism designated 5, as a whole, controlling movable contacts 6, 7, 8, which normally occupy the position in which they are shown in Fig. 2, in which position the station is in receiving condition, and when out of that position, occupy the position in which they are shown in Fig. 1, where the station is in transmitting condition. Contact 6, in the position in which it is shown in Fig. 1, closes a circuit from generator 3, traced as follows: wire 9, contacts 10, 6, wires 11, 12, 13, to right rheostat 1, and from wire 12, by wires 15, 16, 17, to left rheostat 2, and from right rheostat 1 by wires 18, 19, 130, and from left rheostat 2, by wires 21, 19, to the negative pole of generator 3. When contact 6 is in this position (Fig. 1), contacts 7, 8 engage a pair of stationary contacts 22, 23, respectively, thus closing the right and left tracer circuits from the transmitter of such station to the receiver of the distant station, as well as to its own receiver. This is so fully described in the aforesaid Tiffany application that it will be unnecessary to further describe it here beyond merely tracing the right and left hand tracer circuits as thus closed from the right and left rheostats 1, 2, of the transmitter of Fig. 1, to and through the receiver of Fig. 2, namely, the

receiver of the distant station; and also to describe, in detail, in connection therewith, the improvements of the present invention by which the direct current of the generator 3 is converted into alternating currents for the purposes of vibrating the pen moving parts of the receiver, and also effecting the movements of the receiving pen to and from its writing surface. Such circuit, for the 10 right line, consists of roller contact 24, tracer arm 25, wires 26, 27, contact 22, contact 7, wires 28, 29, 30 (Fig. 1), wires 30^a, 29^a, 28^a, contact 7^a, contact 31^a, wire 32^a, wire 34^a, pen moving coil 35^a, and wires 36^a, 15 37^a, and 19^a to ground at 4^a, Fig. 2. Such circuit for the left line consists of roller contact 40, tracer arm 41, wires 42, 43, 44, contact 23, contact 8, wires 45, 46, 47 (Fig. 1), wires 47^a, 46^a, 45^a, contacts 8^a, 48^a, wire 20 49^a, left relay 50^a, (controlling certain local circuits in the receiver), wire 51^a, pen moving coil 52^a, wires 53^a, 54^a, and 19^a to ground at 4^a, Fig. 2.

It will be understood that, as more fully 25 described in the aforesaid Tiffany application, as the transmitting tracer 55 (Fig. 1) is moved laterally in writing, currents, varying in strength in accordance with the position of the contacts 24, 40, lengthwise of 30 their respective rheostats 1, 2, will be shunted into the right and left main line tracer circuits just described; that the coils 35^a, 52^a of the distant receiver (Fig. 2) will be moved rectilinearly thereby in one direction against 35 the tension of springs (not shown), tending to move them in the opposite direction on the core 56^a of the field magnet 57^a, which, with its pole pieces 58^a, provides a suitable magnetic field for such coils; and that as so 40 moved, the coils 35^a and 52^a will move the receiving pen 59^a laterally over its writing field in the same direction, and to the same extent, as the transmitter tracer 55 is moved laterally by the operator at the transmitting 45 station. The magnetic field just referred to is excited from the generator 3^a of Fig. 2 through a local circuit consisting of wire 9^a, contact 10^a, wires 60^a, 61^a, a lock magnet 62^a (of a unison switch group fully described in 50 the aforesaid Tiffany application), wire 63^a, the windings of field magnet 57^a, wires 64^a, 65^a, 66^a, spring contact 67^a mounted on but insulated from armature 68^a of left hand relay 50^a, contact 69^a, and wires 70^a, 71^a, 54^a, and 19^a, to the negative pole of the generator 3^a. This local circuit is opened and closed at a given station, as Fig. 2, at the contacts 67^a, 69^a, and is so closed when another station (as Fig. 1) is transmitting 60 to it and current is therefore on the left main line just described from such other station, relay 50^a being then energized and attracting its armature 68^a which moves contact 67^a into engagement with contact 65 69^a.

It will be understood, of course, that the rectilinear movements just referred to of the coils 35^a, 52^a, will depend, as to extent and direction, upon the strength from time to time of the currents traversing the right 70 and left lines; this, in turn, being dependent upon the extent and direction of the lateral movements of the transmitting tracer 55, and, therefore, the positions of the roller contacts 24, 40, lengthwise of their respective rheostats 1, 2. Such rectilinear movements of the coils 35^a, 52^a, will, in turn, through connections which are diagrammatically shown, but need not be specifically described here, control the lateral movements of the receiving pen 59^a, corresponding in extent and direction to such lateral movements of the transmitting tracer 55. All this is so fully described in the aforesaid Tiffany application that further description thereof in the present case is unnecessary.

The system as thus far described, provides merely for the lateral movements of the receiving pen 59^a in accordance with like 90 movements of the transmitting tracer 55. The system, however, includes means for effecting the movements of the receiving pen 59^a to and from its writing surface as the transmitter tracer is so moved, the means 95 here shown for this purpose being those fully shown and described in the aforesaid Tiffany application, so that they need only be briefly described here. They include, (referring, for convenience, specifically to Fig. 2, as that station is receiving) a polarized pen lifter relay 75^a, a pair of relatively loose contacts 76^a, 77^a, inclosed in a tube 78^a, mounted on a diaphragm 79^a which is vibrated by the relay 75^a when the transmitter tracer 55 rests upon and depresses the transmitter platen switch 80, and a pen lifter electromagnet 81^a, the energization and deenergization of which is effected through contacts 76^a, 77^a by the relay 75^a, 100 so as to effect the movement of the receiving pen 59^a respectively from and toward its record strip. The pen lifter magnet 81^a is included in a branch of the field magnet local circuit heretofore described, such branch circuit being traced as follows: wire 82^a from field magnet 57^a, pen lifter magnet 81^a, wires 83^a, 84^a, contact 76^a, contact 77^a, wires 85^a, 66^a, contacts 67^a, 69^a, and wires 70^a, 71^a, 54^a, and 19^a, to the negative 110 pole of generator 3^a. As fully described in the aforesaid Tiffany application, the contacts 76^a, 77^a, included in this branch circuit, engage each other at their inner ends inside the tube 78^a, and one of them is loose 115 relatively to the other, so that when diaphragm 79^a is vibrated, such contact will be vibrated relatively to the other contact, and thus, in effect, break this branch circuit and deenergize the pen lifter magnet 81^a, with 120 125 130 135

the result that the receiving pen 59^a will then be moved into contact with its record strip as fully described in the aforesaid Tiffany application. Such vibration of the diaphragm 79^a occurs only when vibrations occur in the current traversing the left line tracer circuit, including the relay 50^a, the winding 86^a of the relay 75^a being included in a branch circuit consisting of wire 87^a from wire 49^a, wire 90^a including a condenser 91^a, and wires 92^a, 37^a, and 19^a, to ground at 4^a, Fig. 2; and such vibrations in the left line occur only when the transmitter tracer 55 bears against and depresses its writing platen in a transmitting operation. At other times during a transmitting operation, when there are no such vibrations of the right main line circuit, at which times the transmitting tracer 55 is raised from its writing platen, contacts 76^a, 77^a, are not so vibrated, one relatively to the other, relay 75^a being quiescent, so that pen lifter magnet 81^a is therefore energized and holds the receiving pen 59^a away from its recording surface, which is the position at the time of the transmitting tracer 55 relatively to its recording surface.

I will now describe the means provided by the present invention for vibrations of the pen moving parts in the writing arm 25 for the purpose of minimizing or overcoming the frictional resistance to movements of such parts during a transmitting operation, and I will thereafter describe the means provided by the present invention for producing in the currents traversing the circuit controlling pen lifter relay 75^a the vibrations just referred to, which are necessary for vibrating the diaphragm 79^a, and, through it, the relatively loose contacts 76^a, 77^a, controlling the energization and de-energization of the pen lifter magnet 81^a.

Referring to Fig. 1, it will be observed that the transmitter is provided with a condenser 100 included in a branch of the current supplying circuit heretofore described, such branch circuit consisting of wire 101 from said current supplying circuit, contact 102, armature 103 of an interrupter magnet 104, wires 105, 106, condenser 100, and wire 107 connected with wire 26 leading from tracer arm 25 to the right line circuit heretofore described, to the distant receiver. Intermediate the connection therewith of wire 107 and the tracer arm 25, wire 26 is provided with an impedance coil 108 for a purpose which will presently appear. Interrupter magnet 104 is energized through another branch of this circuit consisting of wire 109, winding of magnet 104, wire 110 containing a resistance 111, and wire 26 to the negative pole of generator 3. During a writing operation, current will be in the branch circuits just described, and so long as armature 103 remains in engagement

with contact 102, condenser 100 will continue to be charged. Current will at the same time, however, pass through magnet 104 by way of wires 109, 110, and 20, and when it reaches a point sufficient to overcome the resistance to movement of its armature 103, it will attract said armature, thus breaking the circuit from current supplying wire 16 through the condenser 100, which will then discharge to ground or to the negative pole 70 of generator 3 through wires 105, 109, armature 104, and wires 110, 20. Interrupter magnet 104 will then become de-energized and release its armature 103, so that the latter will re-engage contact 102 and thus 75 again establish the circuit from wire 16 through the condenser 100, and so on, condenser 100 charging whenever such circuit is so made, and discharging when it is broken, such making and breaking of the 80 circuit occurring with great frequency. This alternate charging and discharging of the condenser 100 converts the direct current of the generator 3 into alternating current 85 waves, which are impressed upon the right line to the distant receiver (Fig. 2). The impedance coil 108 directs these alternating waves over the right line and through the left moving coil 35^a, with the result that such pen moving coil, and, therefore, the 90 pen moving parts connected therewith, are kept, during the transmitting operation, in a condition of vibration such as to effectively overcome frictional resistance to their movement in unison with the transmitting 95 tracer, and this vibration of the coil 35 continues, not only while the transmitting tracer is away from its writing platen, but also while it is in contact therewith.

Coming now to the means provided in the 100 present case for producing in the pen lifter relay 75^a the vibratory condition necessary for the vibration of the diaphragm 79^a and loose contacts 76^a, 77^a, carried thereby, it will be observed on reference to Fig. 1 that 110 the transmitter is provided with a second condenser 115 connected by wire 116 with wire 43 of the left main tracer lines to the distant receiver, and which, in the depressed position of the transmitter platen switch 80, 115 that is to say, when the transmitting pen is in contact with its writing surface and such platen switch therefore depressed, is connected with the current supplying circuit heretofore described from generator 3, by a 120 branch circuit consisting of wire 117, platen switch 80, contact 118, wires 119, 105, armature 103 of magnet 104, contact 102, and wire 101 leading from wire 16 of said current supplying circuit. This condenser 115 125 is charged and discharged respectively on the making and breaking of contact between the armature 103 and contact 102, as in the case of the condenser 100 of the right line, and as it is so charged and discharged, it 130

also converts the direct current of generator 3 traversing the right line into alternating waves which are directed by an impedance coil 120 over the left line to the distant receiver. Some impeding means is necessary in this line for diverting their waves or directing them through relay 75^a. For this purpose I preferably utilize the relay 50^a included in this line circuit; the impedance of such relay and of coil 52^a being such that these alternating waves are backed or forced thereby over wire 87^a, through pen lifter relay 75^a, and thence by wire 90^a, condenser 91^a; and wires 92^a, 37^a, and 19^a, to ground at 4^a. These alternating waves produce in the relay 75^a a vibratory condition causing it to alternately attract and repel with great rapidity or frequency the diaphragm 79^a, with the result that the relatively loose contacts 76^a, 77^a, carried thereby, will be vibrated, one relatively to the other, so as to, in effect, break the circuit (including wires 82^a, 83^a, 84^a, contacts 76^a, 77^a, and wire 85^a) through the pen lifter magnet 81^a, which thus becomes deenergized. As the magnet 81^a is thus deenergized, its armature and the pen rest 121^a carried thereby are withdrawn from pen supporting or engaging position and the receiving pen 59^a therefore moves into contact with its writing platen or record strip; all as more fully shown and described in the aforesaid Tiffany application.

While I prefer to use the impedance coils 100, 120 at the transmitter for directing the alternating waves therefrom to the receiver, and to utilize the relay 50^a for directing such waves, at the receiver, through pen lifter relay 75^a, my invention, broadly considered, is not to be limited thereto, as various other means, either in the way of special devices or special construction of the devices usually present in or connected with the main line or lines, may be used for the purpose.

What is claimed is:

1. In a telautographic system of the variable current-strength type, the combination of a main line circuit between the transmitter and receiver and pen moving parts controlled thereby and in turn controlling the lateral movements of the receiving pen, of a source of direct current supply for the main line, circuit interrupting means and a condenser at the transmitter for converting the direct current into alternating waves on the main line and through such waves vibrating the pen-moving parts, and means at the transmitter for directing such waves from the latter to the receiver.

2. In a telautographic system of the variable current-strength type, the combination of a main line circuit between the transmitter and receiver and pen-moving parts controlled thereby and in turn controlling

the lateral movements of the receiving pen, of a source of direct current supply for the main line, and circuit interrupting means, a condenser and an impedance coil at the transmitter for converting the direct current into alternating waves, directing such waves from the transmitter to the receiver; and through such waves vibrating the pen-moving parts.

3. In a telautographic system of the variable current-strength type, the combination of a main line circuit between the transmitter and receiver, pen-moving parts controlled by the currents traversing said circuit and in turn controlling the lateral movements of the receiving pen, an electromagnet controlling the movements of the receiving pen to and from its writing surface as the transmitting tracer is so moved, a circuit for said magnet including a pair of relatively loose contacts which when relatively vibrated break said circuit, and means at the receiver for so relatively vibrating said contacts, of a source of direct current supply for the main line, circuit interrupting means and a condenser at the transmitter for converting the direct current into alternating waves on the main line and, through said waves and said contact-vibrating means, relatively vibrating said contacts, and means at the transmitter for throwing said interrupter means and condenser into and out of such operative relation to the main line as the transmitter tracer is moved to and from its writing platen.

4. In a telautographic system of the variable current-strength type, the combination of a main line circuit between the transmitter and receiver, pen-moving parts controlled by the currents traversing said circuit and in turn controlling the lateral movements of the receiving pen, an electromagnet controlling the movements of the receiving pen to and from its writing surface as the transmitting tracer is so moved, a circuit for said magnet including a pair of relatively loose contacts which when relatively vibrated break said circuit, and means at the receiver for so relatively vibrating said contacts, of a source of direct current supply for the main line, circuit interrupting means and a condenser at the transmitter for converting the direct current into alternating waves on the main line and, through said waves and said contact-vibrating means, relatively vibrating said contacts, means at the transmitter for throwing said interrupter means and condenser into and out of such operative relation to the main line as the transmitter tracer is moved to and from its writing platen.

5. In a telautographic system of the variable current-strength type, the combina-

tion of a main line circuit between the transmitter and receiver, pen-moving parts controlled by the currents traversing said circuit and in turn controlling the lateral movements of the receiving pen, an electro-magnet controlling the movements of the receiving pen to and from its writing surface as the transmitting tracer is so moved, a circuit for said magnet including a pair of relatively loose contacts which when relatively vibrated break said circuit, and means at the receiver for so relatively vibrating said contacts, of a source of direct current supply for the main line, circuit interrupting means and a condenser connected with the main line at the transmitter for converting the direct current into alternating waves on the main line and, through said waves and said contact-vibrating means, relatively vibrating said contacts, and means at the transmitter for throwing said interrupter means and condenser into and out of such operative relation to the main line as the transmitter tracer is moved to and from its writing platen.

6. In a teletographic system of the variable current-strength type, the combination of a main line circuit between the transmitter and receiver, pen-moving parts controlled by the currents traversing said circuit and in turn controlling the lateral movements of the receiving pen, an electro-magnet controlling the movements of the receiving pen to and from its writing surface as the transmitting tracer is so moved, a circuit for said magnet including a pair of relatively loose contacts which when relatively vibrated break said circuit, and means at the receiver for so relatively vibrating said contacts, of a source of direct current supply for the main line, circuit interrupting means and a condenser connected with the main line at the transmitter for converting the direct current into alternating waves on the main line and, through said waves and said contact-vibrating means, relatively vibrating said contacts, means connected with the main line at the receiver for diverting said waves from the pen-moving parts and to said contact-vibrating means and means at the transmitter for throwing said interrupter means and condenser into and out of such operative relation to the main line as the transmitter tracer is moved to and from its writing platen.

7. In a teletographic system of the variable current-strength type, the combination of a main line circuit between the transmitter and receiver, pen-moving parts controlled by the currents traversing said circuit and in turn controlling the lateral movements of the receiving pen, an electro-

magnet controlling the movements of the receiving pen to and from its writing surface as the transmitting tracer is so moved, a circuit for said magnet including a pair of relatively loose contacts which when relatively vibrated break said circuit, and means at the receiver for so relatively vibrating said contacts, of a source of direct current supply for the main line, circuit interrupting means and a condenser connected with the main line at the transmitter for converting the direct current into alternating waves on the main line and, through said waves and said contact-vibrating means, relatively vibrating said contacts, a circuit controlling relay at the receiver serving to divert said waves from the pen-moving parts and to said contact-vibrating means, and means at the transmitter for throwing said interrupter means and condenser into and out of such operative relation to the main line as the transmitter tracer is moved to and from its writing platen.

8. In a teletographic system of the variable current-strength type, the combination of two main line circuits between the transmitter and receiver and pen-moving parts controlled thereby and in turn controlling the lateral movements of the receiving pen, of a source of direct current supply for the main lines, circuit interrupting means and a condenser at the transmitter for one main line, for converting the direct current into alternating waves on said main line and through such waves vibrating the pen-moving parts, an electro-magnet controlling the movements of the receiving pen to and from its writing surface as the transmitting tracer is so moved, a circuit for said magnet including a pair of relatively loose contacts which when relatively vibrated break said circuit, means at the receiver in the other main line for so relatively vibrating said contacts, a second condenser at the transmitter for said other main line coating with said circuit interrupting means to convert the direct current into alternating waves on said other main line and, through such waves and said contact-vibrating means, relatively vibrating said contacts, and means at the transmitter for throwing said interrupter means and said second condenser into and out of such operative relation to said other main line as the transmitting tracer is moved to and from its writing platen.

9. In a teletographic system of the variable current-strength type, the combination of two main line circuits between the transmitter and receiver and pen-moving parts controlled thereby and in turn controlling the lateral movements of the receiving pen, of a source of direct current supply for the main lines, circuit interrupting means and a condenser at the transmitter for one main

line, for converting the direct current into alternating waves on said main line and through such waves vibrating the pen-moving parts, an electro-magnet controlling the movements of the receiving pen to and from its writing surface as the transmitting tracer is so moved, a circuit for said magnet including a pair of relatively loose contacts which when relatively vibrated break 5 said circuit, means at the receiver in the other main line for so relatively vibrating said contacts, a second condenser at the transmitter for said other main line coacting with said circuit interrupting means to 10 convert the direct current into alternating waves on said other main line and, though such waves and said contact-vibrating means, relatively vibrating said contacts, means at the transmitter for throwing said 15 interrupter means and said second condenser into and out of such operative relation to said other main line as the transmitting tracer is moved to and from its writing platen, and means at the transmitter for directing such alternating waves over each main line from the transmitter to the receiver.

10. In a telautographic system of the variable current-strength type, the combination 30 of two main line circuits between the transmitter and receiver and pen-moving parts controlled thereby and in turn controlling the lateral movements of the receiving pen, of a source of direct current supply for the 35 main lines, circuit interrupting means and a condenser at the transmitter for one main line, for converting the direct current into alternating waves on said main line and through such waves vibrating the pen-moving parts, an electro-magnet controlling the 40 movements of the receiving pen to and from its writing surface as the transmitting tracer is so moved, a circuit for said magnet including a pair of relatively loose contacts which when relatively vibrated break 45 said circuit, means at the receiver in the other main line for so relatively vibrating said contacts, a second condenser at the transmitter for said other main line coacting with 50 said circuit interrupting means to convert the direct current into alternating waves on said other main line and, through such waves and said contact-vibrating means, relatively vibrating said contacts, means at the 55 transmitter for throwing said interrupter means and said second condenser into and out of such operative relation to said other main line as the transmitting tracer is moved to and from its writing platen, and 60 an impedance coil in each main line at the transmitter for directing such alternating waves over such main line from the transmitter to the receiver.

11. In a telautographic system of the variable current-strength type, the combination 65 of two main line circuits between the transmitter and receiver and pen-moving parts controlled thereby and in turn controlling the lateral movements of the receiving pen, of a source of direct current supply for the 70 main lines, circuit interrupting means and a condenser at the transmitter for one main line, for converting the direct current into alternating waves on said main line and through such waves vibrating the pen-moving parts, an electro-magnet controlling the 75 movements of the receiving pen to and from its writing surface as the transmitting tracer is so moved, a circuit for said magnet including a pair of relatively loose contacts which when relatively vibrated break 80 said circuit, means at the receiver in the other main line for so relatively vibrating said contacts, a second condenser at the transmitter for said other main line coacting with 85 said circuit interrupting means to convert the direct current into alternating waves on said other main line and, through such waves and said contact-vibrating means, relatively vibrating said contacts, means connected with said other main line at the receiver for diverting said waves from the pen-moving parts and to said contact-vibrating means, and means at the transmitter for throwing said interrupter 90 means and said second condenser into and out of such operative relation to said other main line as the transmitting tracer is moved to and from its writing platen.

12. In a telautographic system of the variable current-strength type, the combination 95 of two main line circuits between the transmitter and receiver and pen-moving parts controlled thereby and in turn controlling the lateral movements of the receiving pen, of a source of direct current supply for the 100 main lines, circuit interrupting means and a condenser at the transmitter for one main line, for converting the direct current into alternating waves on said main line and through such waves vibrating the pen-moving parts, an electro-magnet controlling the 105 movements of the receiving pen to and from its writing surface as the transmitting tracer is so moved, a circuit for said magnet including a pair of relatively loose contacts which when relatively vibrated break 110 said circuit, means at the receiver in the other main line for so relatively vibrating said contacts, a second condenser at the transmitter for said other main line coacting with 115 said circuit interrupting means to convert the direct current into alternating waves on said other main line and, through such waves and said contact-vibrating means, relatively vibrating said contacts, means at the 120 transmitter for throwing said interrupter means and said second condenser into and out of such operative relation to said other main line as the transmitting tracer is so moved, a circuit for said magnet including a pair of relatively loose contacts which when relatively vibrated break 125 said circuit, means at the receiver in the other main line for so relatively vibrating said contacts, a second condenser at the transmitter for said other main line coacting with 130 said circuit interrupting means to convert the direct current into alternating waves on said other main line and, through such waves and said contact-vibrating means, a circuit controlling relay connected with said other main line at the receiver serving to divert said waves from the pen-moving parts and to said contact vibrating means,

and means at the transmitter for throwing said interrupter means and said second condenser into and out of such operative relation to said other main line as the transmitting tracer is moved to and from its writing platen.

In testimony whereof, I have hereunto set

my hand, in the presence of two subscribing witnesses.

HENRY W. O'NEILL.
